UNITED STATES PATENT OFFICE

HUGO L. BELL, OF NEW YORK, N. Y., ASSIGNOR TO LESQUENDIEU, INC., OF NEW YORK,
N. Y., A CORPORATION OF NEW YORK

DESIGN FOR A TOILET-ACCESSORIES CONTAINER

Application filed November 20, 1930. Serial No. 37,737. Term of patent 7 years.

To all whom it may concern:

Be it known that I, HUGO L. BELL, a citizen of the United States, residing at New York city, county of New York, borough of Manhattan, and State of New York, have invented a new, original, and ornamental Design for a Toilet-Accessories Container, of which the following is a specification, reference being had to the accompanying drawing, forming a part thereof.

I claim:

The ornamental design for a toilet accessories container, as shown.
